[57] CLAIM

The ornamental design for a psaltery, as shown and described.

DESCRIPTION

FIG. 1 is a front perspective view of a psaltery of the present invention, with the opening and strings in phantom;
FIG. 2 is a front perspective view thereof without strings;
FIG. 3 is a front elevational view thereof;
FIG. 4 is a right side elevational view thereof;
FIG. 5 is a bottom plan view thereof;
FIG. 6 is a rear elevational view thereof;
FIG. 7 is a left side elevational view thereof; and,
FIG. 8 is a top plan view.
The broken lines shown are for illustrative purposes only and form no part of the claimed design.
